ROPE THIMBLE

Earle J. Mardis, Chicago, Ill.

Application March 24, 1939, Serial No. 264,045

13 Claims. (Cl. 24—125)

This invention relates to a thimble for wire rope and, more particularly, to an improved rope thimble that will insure equal loading on each of the strands of the rope.

Various types of rope clamps or thimbles have been suggested and commercially used. Most of these types, especially that commonly known as the wedge socket type have not proved very successful in that the wedge produces a greater bearing force against one or more strands of the rope, which results in a greater portion of the load being carried by those strands. Such a condition causes an unbalanced load on the strands of the rope which is, of course, very undesirable.

It is an object of this invention to provide an improved rope thimble which will bear equally on each of the strands of the rope.

It is another object of this invention to provide a rope thimble which will securely hold the extreme dead end of the rope while the looped adjacent portion toward the live end thereof is threaded and properly placed under tension in the thimble clamp.

Various other objects and advantages of my invention will more fully appear during the course of the following specification and will be particularly pointed out in the appended claims.

In the accompanying drawing, I have shown, for the purpose of illustration, one preferred embodiment and a slight modification thereof which my invention may assume in practice.

In the drawing:

Figure 1 is a side elevation, showing the improved rope thimble of the preferred form of my invention assembled on the end of a rope;

Figure 2 is a plan thereof;

Figure 3 is a sectional view taken on the line III—III of Figure 2;

Figure 4 is a plan view similar to Figure 2 showing a slightly modified construction of the rope thimble of my invention; and,

Figure 5 is a sectional view taken on the line V—V of Figure 4.

Referring more particularly to the drawing, the preferred embodiment of the improved rope thimble of my invention, as shown in Figures 1, 2 and 3, comprises a plate-like member 2 having a thin body portion 3 diverging outwardly into a thickened semi-circular shaped outer end portion 4 having a groove 5 arranged in the edge around the periphery thereof.

There is provided a co-acting plate-like member 6 of substantially the same thickness as the thin body portion 3 of the plate-like member 2 which is adapted to abut against the inner edge

of the thickened portion 4 thereof. The plate-like member 2 has grooves 7 and 7a on the inner surface thereof which correspond with grooves 8 and 8a, respectively, on the inner surface of the plate-like member 6 and are adapted to receive a rope 9. The corresponding grooves 7 and 8 on the side of the thimble adapted to hold the live end of the rope have preferably a smooth surface while the corresponding grooves 7a and 8a on that side of the thimble adapted to hold the rope 10 toward the dead end thereof are preferably corrugated or otherwise provided with suitable means for gripping the same. The plate-like member 6 is held in co-acting relationship with the plate 2, preferably by means of machine screws or suitable bolts 10 placed along the edges and in the center thereof and it will be understood that the two plate-like members are adapted to hold the rope therebetween toward the live end thereof. The inner edge of the plate-like member 6 is 15 preferably cut away as at 12 so as to receive a substantially rectangularly shaped segmental plate-like member 13. This segmental member 13 preferably has a corrugated groove 14 arranged on the inner surface thereof and is adapted to 20 co-act with the plate-like member 2 to securely hold and clamp the extreme end of the dead end of the rope, preferably by means of machine screws 15 placed on each side thereof.

The thickened end portion 4 has preferably a 30 hole 16 arranged therein, for thimble attachment purposes, and is positioned preferably in alignment with the live end of the rope. This hole 16 is preferably lined by means of a suitable removable bushing member 17.

In Figures 4 and 5 there is shown a slight modification of the improved rope thimble of the present invention. This modified construction is similar to the preferred construction but instead of using a segmental plate-like member 13 in the 40 inner cut-away edge portion at 12 of the co-acting plate-like member 6, a pair of U-bolts 18 are provided for co-acting with the plate-like member 2 for holding the rope toward the dead end thereof. It will be understood, of course, that 45 any other suitable bolts or means may be provided for co-acting with the plate-like member 2 to hold the end of the rope toward the dead end thereof in place of the segmental member 13 or the U-bolts 18. In this construction the 50 co-acting plate-like member 6 preferably has arranged therewith an outer extending lug portion 19 which is adapted to extend to one side of the live end of the rope into the cut-away portion at 12 so as to provide a means for receiving an 55

additional machine screw or clamping bolt 20, as is clearly shown in Figure 4 of the drawings.

As a result of my invention, it will be seen that there is provided a relatively thin and flat rope thimble, and that the dead end of the rope can be securely clamped in position by means of the segmental clamp 13 or U-bolts 18 and the adjacent portion of the rope toward the live end thereof threaded or looped under tension between the plate-like members 6 and 7 and securely clamped therebetween without any damage thereto. It will also be seen that the rope thimble of this invention is clamped securely over substantially the entire loop of the rope, thereby eliminating the danger of any slippage or distortion whatsoever of any of the strands or that part of the rope looped around the thimble.

The present application is a continuation-in-part of applicant's copending application, Serial No. 202,347, filed April 15, 1938.

While I have, in this application, specifically shown and described one embodiment and a modification thereof which my invention may assume in practice, it will be understood that this embodiment is merely for the purpose of illustration and description and that various other forms may be devised within the scope of my invention, as defined by the appended claims.

I claim:

- 30 1. A rope thimble consisting of three plate-like members, one of said members adapted to co-act with another of said members to securely hold the dead end of a rope, and the third one of said members adapted to co-act with said first-mentioned member to securely hold the adjacent portion of the rope toward the live end thereof, said second and third members being disposed substantially in the same plane.
- 40 2. A rope thimble comprising a plate-like member having a thin body portion and a thickened end portion, a co-acting plate-like member adapted to abut against the thickened portion of the first-mentioned member and a segmental member disposed substantially in the same plane with that of said second-mentioned member which is adapted to co-act with said first-mentioned plate member to securely hold the dead end of a rope, said second-mentioned member adapted to co-act with said first-mentioned member to securely hold the adjacent portion of the rope toward the live end thereof.
- 50 3. A rope thimble comprising a plate-like member having a thin body portion diverging outwardly into a thickened end portion, a plate-like member adapted to co-act with the thin body portion of said first-mentioned plate-like member in abutting relationship with the thickened portion thereof, and a segmental plate member adapted to fit in the inner edge of said last-mentioned plate-like member, said last-mentioned plate-like member and segmented plate-like member adapted to co-act with said first-mentioned plate-like member to securely hold the end of a rope therebetween.
- 60 4. A rope thimble comprising a plate-like member having a thin body portion diverging outwardly into an end portion having a thickness substantially twice that of the thin portion, a co-acting plate-like member having a thickness corresponding to the thickness of the thin body portion of the first-mentioned member, and a segmental plate-like member adapted to fit in the inner edge of said second plate-like member and co-acting with said first-mentioned member to securely hold the dead end of a rope, said second-

mentioned plate-like member adapted to abut against the thickened end portion of the first-mentioned member and to co-act therewith to securely hold the adjacent portion of the rope toward the live end thereof.

5 5. A rope thimble consisting of three plate-like members, two of said members disposed in substantially the same plane and adapted to cooperate with the third member to securely hold a rope therebetween.

10 6. A rope thimble comprising a plate-like member, a co-acting similar plate-like member consisting of two separate parts oppositely disposed from said first-mentioned member, one of said parts adapted to cooperate with said first-mentioned member to securely hold a rope therebetween toward the live end thereof and the other part adapted to cooperate with said first-mentioned member to securely hold the rope toward the dead end thereof.

15 7. A rope thimble comprising a plate-like member having a pair of spaced apart grooves arranged in one face longitudinally thereof, a similar plate-like member consisting of at least two separate parts disposed oppositely from said first-mentioned member, one of said parts having a pair of similar spaced apart grooves arranged therein disposed oppositely from the grooves in said first-mentioned member, and the other part thereof having a single similar groove arranged 20 therein which is disposed oppositely from one of the grooves in said first-mentioned member, both parts of said second-mentioned plate-like member adapted to cooperate with said first-mentioned plate-like member to retain a rope therebetween.

25 8. A rope thimble comprising a platelike member having a pair of spaced apart grooves arranged in one face longitudinally thereof, a similar plate-like member disposed oppositely from said first-mentioned member having a portion thereof cut away, said second-mentioned member having a pair of similar spaced apart grooves longitudinally arranged in the face thereof opposite the grooves in the first-mentioned member, and a third plate-like member disposed in said cut-away portion of said second-mentioned member, said third plate-like member having a single similar groove arranged therein opposite one of the grooves in said first-mentioned member, both of said second and third-mentioned members adapted to cooperate with said first-mentioned member to retain a rope therebetween.

30 9. A rope thimble comprising a plate-like member having a pair of spaced apart grooves arranged in one face thereof and a thickened end portion around which the rope is adapted to pass, a co-acting plate-like member consisting of two separate parts disposed oppositely from said first-mentioned member, one of said parts abutting against said thickened end portion of said first-mentioned member and having a pair of similar spaced apart grooves arranged therein opposite from those of said first-mentioned member, and the other part thereof having a single similar 35 groove arranged therein disposed oppositely from one of the grooves in said first-mentioned member, the first-mentioned part of said second-mentioned member adapted to cooperate with said first-mentioned member to securely hold that portion of the rope toward the live end thereof and the second-mentioned part adapted to securely hold that portion of the rope toward the dead end thereof.

40 10. A rope thimble comprising a plate-like

member adapted to be disposed on one side of the rope, a co-acting member adapted to be disposed on the opposite side of the rope from said plate-like member so as to cooperate therewith to securely hold the rope therebetween toward the live end thereof, and another member disposed on the same side of the rope as said last mentioned member and adapted to cooperate with said plate-like member to securely hold the rope therebetween toward the dead end thereof.

10 11. A rope thimble comprising a plate-like member adapted to be disposed on one side of the rope, a co-acting similar plate-like member adapted to be disposed on the opposite side of the rope from said first-mentioned member, said second-mentioned plate-like member adapted to cooperate with said first-mentioned member to securely hold the rope therebetween toward the live end thereof, and means independent of said second-mentioned member adapted to be disposed on the same side of the rope as said second-mentioned plate-like member and which is adapted to cooperate with said first-mentioned member to securely hold the rope therebetween toward the dead end thereof.

15 16 17 18 19 20 21 22 23 24 25 12. A rope thimble comprising a plate-like member, a co-acting similar plate-like member

oppositely disposed from said first-mentioned member having an opening in the edge thereof, said second-mentioned member adapted to cooperate with said first-mentioned member to securely hold a rope therebetween toward the live end thereof, and another member disposed in the opening of said second-mentioned member which is adapted to cooperate with said first-mentioned member to securely hold the rope therebetween toward the live end thereof.

10 11 12 13 14 15 16 17 18 19 20 21 22 23 24 25 13. A rope thimble comprising a plate-like member adapted to be disposed on one side of the rope, a co-acting plate-like member adapted to be disposed on the opposite side of the rope from said first-mentioned plate-like member, said second-mentioned plate-like member adapted to cooperate with said first-mentioned plate-like member to securely hold the rope therebetween toward the live end thereof, at least one U-bolt member adapted to be disposed on the same side of the rope as said second-mentioned plate-like member and which is adapted to cooperate with said first-mentioned plate-like member to securely hold the same therebetween toward the dead end thereof.
